UNITED STATES PATENT OFFICE.

HARRY B. McBEE, OF ST. LOUIS, MISSOURI.

LOOSE-LEAF BINDER.

Application filed September 4, 1925. Serial No. 54,395.

My invention relates to binders for loose leaf filing, and particularly to binders adapted to clamp, by adjustable and movable means, the leaves which are filed, and 5 also provide for adding to, or taking from, the quantity filed.

The object of my invention is to provide a simple, durable and practically inexpensive, binder which may be easily and quickly 10 operated for releasing pressure upon leaves filed, so that ready access may be had to the same, and such leaves as desired removed therefrom, or any quantity, up to the capacity of the file, be added thereto.

15 My invention consists of certain details of construction hereinafter set forth, pointed out in my claims, and illustrated in the accompanying drawings, in which—

Fig. 1 shows a side elevation view, partially in section, of my improved binder;

Fig. 2 shows a perspective view of a part of my binder, the dotted line indicating the movable position of the upper cover and clamping means when the securing rod has 25 been removed;

Fig. 3 and Fig. 4 indicates the manner in which the body portion of my clamping means is secured to the back of the file;

Fig. 5 is a front elevation view of the 30 body portion of the clamping means after it is secured to the back.

Referring to the accompanying drawings the reference numeral 10 is used to indicate the bottom cover of my file, the numeral 11 the top cover, and the numeral 12 the back, the back and covers being joined in the usual flexible manner by, preferably, cloth strips pasted to, and joining, the back and covers. Extending upwardly from the 35 bottom cover are a plurality of securing posts 13 designed to function for receiving perforated sheets 14. The numeral 15 indicates a lock plate, preferably formed of metal, perforated to fit over the posts 13 and also having its inner end extending beyond the filed sheets and towards the back, there being a perforation, preferably centrally located, in this extending portion and beyond the line of the filed sheets, to receive 45 the securing rod, or pin, 16.

To the back 12 I have secured the body portion of my securing means which consists of a plate 17, provided centrally and longitudinally with a forwardly projecting 50 portion 18, this portion being slotted trans-

versely, as at 19, the slots being of sufficient width to receive the plate 15. The projecting portion 18 projects forward sufficiently to form between the plate and the back 12 a channel to receive the pin 16.

The body portion 17 of my locking means is provided with hook extensions 20 adapted to curve over the back and clamp into the rear surface of the back, thereby securely and rigidly securing the body portion 17 65 to the back 12. This construction is shown in Figures 3 and 4, the lower hook in Fig. 4 being clamped into the back, and the upper hook being in its normal position as it comes from the die and ready to be bent 70 down and clamped into the back.

It is obvious that the part 18 of the body portion and the central orifice in the plate 15 are so arranged that in assembled position with the plate 15 extending into one of the slots in a protruding portion 18, the central orifice in the plate 15 will lie within the channel formed between the projecting portion 18 and the back 12.

In the practical operation the sheets 14, 80 to be filed, are threaded on the posts 13. The plate 15 is then also threaded on the posts 13 and forced downwardly until it compresses the sheets 14. At this time the back 12 is lying away from the sheets and it 85 is now brought forward and the body portion 17, carried by the back, is moved forward, the plate 15 entering one of the slots 19. The securing rod, or pin, 16, is then threaded downwardly through the channel 90 formed between the projecting portion 18 and the back 12, and through the orifice in the plate 15 which extends into this channel. It is obvious this firmly locks the back to the plate 15, and the plate 15 is rigidly held 95 in its position by means of the posts 13, and the plate 15 entering into one of the slots 19 and the rod 16 locking it.

In my drawings I have illustrated a preferred form of construction for my invention but I do not wish to be understood as limiting my protection to the specific structure as shown and described, for my invention contemplates other forms of construction, as will be obvious.

Having thus described my invention, what I claim and desire to secure by Letters Patent of the United States is:

1. A loose leaf binder comprising a bottom cover, a top cover and a back, joined by 110

flexible means; a plate, provided with a centrally protruding portion, secured to the back, and transverse slots in said plate; filing posts secured to the lower cover; a lock 5 plate, orificed to fit over the filing posts, constructed so as to protrude toward the back and beyond the sheets to be filed, and being of such thickness as to be adapted to enter the slots in the aforesaid plate, there being 10 an orifice in said locking plate so arranged as to lie within the slotted portion of the back plate; a securing pin adapted to lie within the protruding portion of the back plate and to pass through the orifice in the locking 15 plate, substantially as shown and described.

2. A loose leaf binder comprising an upper and lower cover and a back, flexibly joined together; a back plate, having a central raised portion provided with transverse 20 slots therein, secured to the back; filing posts on the lower cover; a locking plate orificed to ride on said posts, the inner end of said plate being orificed, said inner end being adapted to selectively lie within one of the 25 slots in the back plate; a securing pin adapted to be threaded into the protruding portion of the back plate and to pass through

the orifice in the locking plate, substantially as shown and described.

3. A loose leaf binder comprising a lower 30 cover, an upper cover and a back, flexibly joined together; filing posts on the lower cover; a locking plate orificed to ride on said filing posts and extend inwardly beyond the sheets to be filed, there being an orifice centrally near the inner edge thereof; a receptacle secured to the back; means whereby the forward end of the locking plate extends into the receptacle secured to the back of the volume, and means to lock the plate in said 40 receptacle.

4. A loose leaf binder comprising a lower cover, an upper cover and a back, hinged together; a back plate provided with transverse channels, secured to the back; filing 45 posts on the under cover; a lock plate threaded on said filing posts and adapted to selectively fit into the slots in the back plate, there being an orifice in that portion of the locking plate which extends into the afore- 50 said slot; a securing pin to pass through the orifice in the locking plate and secure it to the back plate.

HARRY B. McBEE.
